UNITED STATES PATENT OFFICE.

HARRY T. KINGSBURY, OF KEENE, NEW HAMPSHIRE.

AUTO-AERIAL LADDER-TRUCK.

No. 818,261.

Specification of Letters Patent.

Patented April 17, 1906.

Application filed September 29, 1905. Serial No. 280,641.

To all whom it may concern:

Be it known that I, HARRY T. KINGSBURY, a citizen of the United States, residing at Keene, in the county of Cheshire, State of 5 New Hampshire, have invented certain new and useful Improvements in Auto - Aerial Ladder-Trucks, of which the following is a description, reference being had to the accompanying drawings, and to the figures of 10 reference marked thereon.

The principal object of the present invention is to provide a novel and attractive toy in the form of a ladder-truck, in which the truck is propelled by a suitable motor and 15 carries an automatically-raised ladder.

A further object of the invention is to provide a spring-elevated ladder having a suitable means for retarding or governing the speed at which the ladder is raised.

20 A still further object of the invention is to provide a normally restrained spring-elevated ladder and a self-releasing latch or starting device which may be moved to allow the ladder to rise.

25 With these and other objects in view my invention consists in the construction and combination of elements hereinafter described, illustrated in the accompanying drawings, and particularly pointed out in the 30 claims.

Referring to the drawings, Figure 1 is a side elevation, partly in section, of a toy constructed in accordance with the invention, the ladder being in horizontal position on the 35 truck. Fig. 2 is a similar view of the front end of the device, the ladder being elevated. Fig. 3 is a detail perspective view of the releasing-catch and its connected parts. Fig. 4 is an enlarged view of the speed-governing 40 device.

Similar numerals of reference are employed to indicate corresponding parts throughout the several figures of the drawings.

The truck is preferably formed of stamped 45 sheet metal and comprises longitudinal sills 1, mounted on suitable front and rear wheeled axles 2 3. The rear axle includes a driven member that is propelled by a spring-motor 4, having a suitable winding-key 5, the motor 50 driving one or both of the rear wheels, and thus propelling the truck. At the front of the frame is a suitable seat 6 for a wheelsman or chauffeur.

The longitudinal sills are provided with 55 vertically-arranged lugs 8, carrying a pivot-

pin or cross-bar 9, on which are pivoted the ears 10 of a sheet - metal bracket 11, said bracket being arranged to embrace and firmly clamp the lower ends of the side rails of a ladder and being strengthened by an integral cross-bar 12. On the pivot-pin is also mounted a toothed segment 15, that is provided with an integral lug 16, notched for the reception of the cross-bar. The segment is held in a central position by means of a cross-bar 17, having perforated ears for the passage of the pivot-pin and provided on its opposite sides with pendent flanges 19 slit, or grooved for the reception of the segment.

The lugs 8 previously referred to form the 70 ends of a strip 20, that extends transversely across the frame below the sills and is provided with openings for the reception of the arbor 20' of an anchor 21 in the form of a pair of spaced curved bars weighted at their 75 opposite ends and carrying cross - pins 22, that form pallets for engagement with the teeth of the segment, the mechanism being in the form of an escapement for retarding or controlling the upward movement of the 80 ladder.

The ladder is preferably formed of wood and comprises a lower section 24 and an upper section 25, the adjacent ends of which abut when the ladder is elevated. Each 85 section carries a bracket 26, having projecting ears 27, that are connected by a pivot-pin 28. Coiled around the pin is a torsion-spring 29, having its ends connected to the respective ladder-sections, this spring serving 90 as the ladder-elevating means.

From the lower portion of the upper ladder-section 25 extends a connecting member 30, the lower end of which is connected to a loop 31, carried by the frame or seat member, 95 and while this connecting member may be in the form of a non-extensible rod it is preferably made in two sections that are connected by a relief-spring 33, so that the ladder may be folded down in any manner. If the ladder is folded as it is lowered, the spring is not brought into play; but if the two ladder-sections are first turned down flat before the upper ladder is folded over the spring is placed under stress. When the ladder is lowered, 100 its rear end is received on a rest 34, which may form a part of the motor-carrying frame, and the sides of the rest have upturned lips or flanges 35 to prevent lateral movement of the ladder. Extending across the frame is a pivot- 110

pin 36, on which is mounted a catch 37, arranged to engage one of the rungs of the upper ladder-section, and said catch is preferably bifurcated at its upper end to permit the 5 passage of the connecting member 30.

The front cross-bar 38 of the frame has guiding-openings for the passage of the parallel arms of a U-shaped trip 39, the rear ends of said arms being pivoted in ears 40 on the 10 catch. The front cross-bar of the trip projects beyond the front of the frame, so that when it touches a wall, desk, table-leg, or other obstruction the catch will be thrown back, automatically releasing the ladder and 15 allowing it to rise to the vertical position. The elevating-spring cannot act to throw the ladder up suddenly, the speed being governed by the escapement mechanism previously described.

20 Having thus described my invention, what I claim as new, and desire to secure by Letters Patent, is—

1. A toy ladder-truck having a spring-elevated ladder, and automatic means for governing the speed of movement of the ladder.

2. A toy ladder-truck having a movable ladder, means for elevating the same, and automatic mechanism for retarding or governing the movement of said elevating means.

3. A toy ladder-truck having a movable ladder, a spring for elevating the same, and an automatic governing device for retarding the action of the spring.

4. A toy ladder-truck, a ladder pivotally connected thereto, a spring for elevating the ladder, and an escapement mechanism for governing the speed of movement of the ladder.

5. A toy ladder-truck, a ladder pivoted 40 thereto, an escapement member carried by and movable with the ladder, a spring for elevating the ladder, and an escapement-anchor supported by the truck-frame and co-acting with said escapement member to retard or govern the movement of the ladder.

6. A toy ladder-truck, a ladder pivotally connected thereto, a toothed segment secured to and movable with the ladder, an escapement-anchor carried by the truck-frame 50 and comprising a pair of spaced arms having weighted outer ends and provided with cross-pins forming pallets, and a spring for elevating the ladder.

7. A toy ladder-truck, an automatically-elevated ladder carried thereby, a catch acting against the elevating device to hold the ladder in lowered position, and means for releasing the catch; substantially as described.

8. A toy ladder-truck, an automatically-elevated ladder carried thereby, a catch for engaging and holding the ladder in lowered position, and means for transmitting release movement to said catch.

9. A toy ladder-truck, an automatically-elevated ladder supported thereby, and an

obstacle-engaging catch normally holding the ladder in lowered position.

10. A toy ladder-truck, a ladder pivoted thereto, a catch for holding the ladder in lowered position, and a catch trip-bar projecting 70 in front of the truck and operable by engagement with any obstacle in the path of the truck.

11. A toy ladder-truck, a ladder pivotally connected thereto, a spring for elevating the 75 ladder, a pivotally-arranged catch normally holding the ladder in lowered position, and a U-shaped trip-bar connected to the catch, and extended to the forward end of the truck in a position to be engaged by any obstacle in 80 the path of movement of the truck.

12. A toy ladder-truck, a ladder pivotally connected thereto, said ladder being formed of a pair of pivotally-connected sections, the ends of which are designed to abut when the 85 ladder is elevated, an elevating-spring at the juncture of the two ladders and tending to elevate the same, and means connecting the upper ladder-section to the truck-frame, whereby unwinding movement of the spring 90 will raise the lower ladder-section and throw the whole ladder forward.

13. A toy ladder-truck, a ladder pivotally connected thereto and formed of a plurality of pivotally-connected sections, a torsion-spring 95 arranged at the juncture of two sections of the ladder and tending to separate the same, and a spring-connecting bar extending between the upper ladder-section and a stationary portion of the truck-frame.

14. A toy ladder-truck, a pivot-pin supported by the frame of the truck, a ladder, a bracket clamped to the ladder and having ears through which the pivot-pin passes, a toothed segment mounted on the pivot-pin 105 and having a notched projection engaging the bracket, a cross-bar having end ears through which the pivot-pin passes and provided with depending notched sides arranged to receive the segment and hold the latter in a central position, an anchor pivoted to the frame and engaging the teeth of the segment, and a spring for elevating said ladder.

15. In a toy ladder-truck, the combination 115 with a frame and running-gear, of a motor element for driving the truck, a seat at the front end of the truck, a ladder pivoted to the forward end of the truck, a ladder-rest arranged near the rear edge of the truck, a spring for elevating the ladder, an obstacle-engaging catch normally holding the ladder in lowered position, and means for governing the speed at which the ladder is elevated.

16. In a toy ladder-truck pivotally connected ladder-sections supported thereby, means for elevating the latter, including an elevating-spring arranged at the juncture of two of the ladder-sections, a catch device for holding the ladder-sections in retracted posi- 125 130

tion, and a trip for releasing said catch; substantially as described.

17. In a toy ladder-truck, a series of ladder-sections, a spring for elevating the same, a catch for holding the ladder in lowered position, and a trip device projecting from the truck and operable by engagement with an obstacle in the path thereof to release the

catch and allow the ladder-sections to be elevated; substantially as described.

10 In testimony whereof I affix my signature in presence of two witnesses.

HARRY T. KINGSBURY.
